ELECTRIC RELAY

Herbert R. Warnke, Orange, and Leon G. Barry, Whippany, N. J., assignors to United States Instrument Corporation, Summit, N. J., a corporation of New Jersey

Application March 16, 1951, Serial No. 215,917

3 Claims. (Cl. 200—93)

This invention relates to electric relays such as are used to communicate the change in weak electric current or of a small electrical impulse to another device for operating the device directly or for opening and closing an electric circuit to energize the device, for example to produce a signal. To operate efficiently, a relay must be highly sensitive to the electrical impulses that it receives and relays are, therefore, usually of delicate construction. However, a delicately constructed relay is not suited for uses in apparatus that operates under conditions of severe shock and vibration, because the relay is easily disturbed and may at times be moved by a slight jar or other motion to a position that causes actuation of the device to which the relay is connected, thereby for example, producing a false signal. In many applications and especially those where conditions of mechanical shock and vibration are encountered, it has been found necessary, therefore, to make the relay of heavy design, as the result of which sensitivity is sacrificed to obtain increased stability.

A general object of the invention is to provide an electric relay that is reliable and highly sensitive to changes in electric conditions and yet is adapted to resist movement due to mechanical shock or vibration. More specifically an object of the invention is the provision of a relay operated switch mechanism that may be moved by a weak electric impulse and then remain stable in its open or closed position unaffected by extraneous influences.

A further object is to provide a relay mechanism that is adapted to respond rapidly to a change in electric conditions and communicate the occurrence of this change to one or several devices and to maintain its effect upon such devices until the mechanism is reset by an operator.

Further objects and various advantages of the invention will become apparent from the following description of a preferred form thereof, reference being made to the accompanying drawing, in which:

Figure 1 is a plan view of a relay operated switch and signalling mechanism, constructed according to the invention;

Figure 2 is a left end elevation of the mechanism of Figure 1, showing an embodiment in which a preferred form of the relay may be used to operate two contact switches;

Figure 3 is a bottom plan view of the mechanism of Figure 1;

Figure 4 is a right end elevation of the mechanism of Figure 1;

Figure 5 is a longitudinal section taken on line 5—5 of Figure 3;

Figure 6 is a longitudinal section taken on line 6—6 of Figure 3;

Figure 7 is a sectional view on line 7—7 of Figure 6; and

Figure 8 is a view similar to Figure 4, but with the signalling plate thereof removed to show the relay in end elevation.

Referring now to the drawing, the relay shown therein comprises an electric motor with two electromagnets arranged side by side and a rotor positioned between the heads or the pole pieces of the electromagnets. For convenience in describing the details of construction of the embodiment shown in the drawing, the right hand end of the mechanism as seen in the view of Fig. 1 will be referred to hereinafter as the front end of the mechanism while the left hand end of the mechanism will be referred to as the rear end thereof.

The field coils for the motor are designated by the

2

numerals 10 and 11 and each of them consists of a coil of insulated wire wound around a spool 12 (Fig. 5), of dielectric material and having a tubular core with a flange on each end thereof. The front ends or pole pieces 13 of the cores 14 and 15 for the coils 10 and 11, respectively, are larger in diameter than are the shanks 16 of cores.

The elements comprising the motor are mounted on a plate 17 having holes 18 therein for accommodating the shanks 16, and the cores are secured to the plate 17 by staking or otherwise. The head portion 13 of the cores extend to the front from the mounting plate 17 while the shanks 16 extend from the rear side of the plate. The field coils 10 and 11 on the spools 12 are then fitted over the shanks of the cores to form the electromagnets of the motor.

In order to prevent the field coils from rotating on their respective cores, the flanges of the spools 12 are formed substantially as a square, and a spacer 19 is inserted between the adjacent coils whereby the straight edges of the flanges of the spools lie against the faces of the spacer to fairly anchor the coils on the cores. The spacer 19 is supported at its front end on the mounting plate 17 while its rear end is carried on the back plate 20 of a suitable magnetic metal and fixed to the ends of the pole piece 25 shanks by means of the screws 21.

As best shown in Fig. 7 the rotor assembly is positioned between opposed cylindrically concave faces of the pole pieces or head portions of the cores. This assembly comprises a short cylindrical permanent magnet 22 having its poles along the sides of the cylinder, i. e. each of the opposite poles of the magnet is perpendicular to the axis of the cylinder 22. The magnet has an axial bore 23 to accommodate a shaft 24 journaled in the mounting plate 17 at the bearing 25 which in turn is located at the mid-point of a line drawn between the axes of the pole pieces. A casing 26 is provided to cover the pole pieces 13 and the rotor 22 for shielding these parts from injury and from dust that might settle on them and reduce efficiency of the motor. In front of the casing 26 and substantially covering its base portion is a clamping plate 27 having a bearing hole 28 through which the front end of the shaft 24 extends. A hole 29 is also provided in the base of the casing 26 for the shaft 24. Casing 26 and clamping plate 27 are held in place by means of the screws 30 which are tightened into suitably aligned holes in the front ends of the pole pieces.

The shaft 24 is firmly secured in the axial bore of the cylindrical magnet 22 and it rotates with the magnet in bearings 25 and 28. Complete rotation of the rotor or magnet 22 is prevented by means of a stop finger 31 carried by the magnet and a spring stop arm 32 supported on the mounted plate 17. As shown in the drawing, the stop finger 31 may comprise a projection extending from the rim of a small disc 33 which is splined on the shaft 24 in abutting relation to a shoulder 34. When the magnet rotates, the disc 33 with the stop finger 31 will rotate with the magnet until the finger strikes against the spring 32, whereby further rotation of the magnet in the same direction is prevented.

When there is no electric current flowing in the field coils 10 and 11, the pole pieces will exert no magnetic force on the rotor magnet 22; but, since the magnet 22 is a permanent magnet, it will rotate to a position where its magnetic poles are juxtaposed to the pole pieces 13. In other words the permanent magnet rotor will tend to rotate into a position between the pole pieces which provides the magnetic path of lowest reluctance. This will be in line with the pole pieces in either of two positions 180° apart. The rotor is manually set in one of these 70 positions, the stop 31 engaging the spring 32 to prevent the rotor from being set exactly in line with the pole pieces and to bias the rotor in one direction.

For a complete explanation of the action of rotor magnet 22, reference will be made in particular to Fig. 7 of the drawing where the spring 32 biases the rotor to rotation clockwise. Let it be assumed for purposes of this explanation, that the portion of the magnet 22 to the right of stop 31, as seen in Fig. 7, is a north pole and the left hand portion of the magnet is a south pole. 75 With this relation of the stop 31 to the poles of the magnet, the field coil 10 will be fitted on the shank of

the pole pieces 14 in a way that the direction of the winding of the coil will cause the head portion of pole piece 14 to become a north pole when the coil is electrically energized. In a similar way, the head portion of pole piece 15 will be a south pole when its coil 11 is energized. The coils 10 and 11 are connected in the same electrical circuit so that they will become energized simultaneously. Since like magnetic poles repel each other, it will be seen that when the field coils 10 and 11 are energized by a direct current, the magnet 22 will rotate on its shaft 24 in the direction in which it is biased by the spring 32 until its north pole faces toward the south pole piece 15 and its south pole faces pole piece 14, causing the magnet to stop rotating. During this rotation of the magnet 22, the stop 31 will have been turned to a point that is about 180° removed from the position of the stop shown in Fig. 7. The magnet with its stop will then remain in this rest position regardless of whether the electromagnets are subsequently de-energized and energized again, unless, of course, the polarity of the pole pieces should be reversed, which is not the case in this invention since they are arranged to be energized only by direct current and not by alternating current. When the magnet has reached this rest position and the electromagnets are de-energized, the poles of the rotor magnet will exert a pull on the pole pieces. If, therefore, the mechanism happens to become subjected to a severe shock or vibration, the rotor will still tend to remain in its rest position. To operate again the rotor must be turned manually against the pull of the magnet to its reset position where the stop 31 strikes the bias spring 32. The rotor will then tend to remain in its rest position, unaffected by mechanical shock and vibration, until the coils are again energized.

The stop 31 is made wide enough that when it is located in a reset position, i. e. against either of the sides of the bias spring 32, it will maintain the poles of the rotor magnet 22 out of direct alignment with the center of the pole pieces. This is done in order to eliminate the possibility that the rotor may tend to turn in a direction to keep the stop up against the bias spring. When the stop 31 is positioned to the right of the bias spring 32, as seen in Fig. 7, the axis of the right hand pole of magnet 22 will be positioned below the axis of the magnetic pole of core 14, and the rotor will turn in a clockwise direction upon energizing of the field coils. When the stop 31 is reset to the left of spring 32, and the electric circuit for the field coils is closed, the rotor will turn counter-clockwise. Thus, the stop 31 provides a means for predetermining the direction of rotation of the rotor.

It is clear from the above description of the method of operation of the rotor 22 that in order to move the rotor from a reset position to its rest or inactive position, under normal conditions, the field coils must be energized for only such time as is sufficient to turn the rotor enough that each of its magnetic poles are more than 90° removed from a like pole in the pole pieces. If the rotor were slowly rotated to less than such position by the time that the field coils became de-energized, the rotor would snap back to its reset position due to the force of its magnetic pull on the pole pieces. It follows, also, that if it be desired to have the rotor rotate from its reset position in one direction only, then the bias spring 32 may be positioned close to a pole piece, whereby the poles of the magnet will be only slightly less than 90° removed from a pole piece and an electrical charge of very short duration would be necessary to cause the rotor to turn to its rest position.

If a relatively strong direct current is passed through the coils, the rotor would move from its reset position at a high speed. In such case and where the parts of the relay are carefully synchronized, the rotor may be made to rotate to its rest position even though the field coils be de-energized where a pole of the magnet is less than 90° removed from like poles of the electromagnets. This occurs because the momentum of the rotor when rotating at a fast rate carries it to a position where its poles will each be attracted to the next pole piece.

In accordance with the invention the rotor also operates a switch mechanism a section of which is connected in circuit with the coils 10 and 11 to open the circuit through said coils as the rotor passes 90°. This is accomplished by the provision of a cam associated with the rotor and a connection between said cam and a switch.

In the illustrated embodiment a pair of contact switch assemblies 35 and 36 are fastened by screws 37 to the base of mounting plate 17. It will be apparent, however, that the relay may operate any number of such switch assemblies, and that it will function properly if connected to only one switch assembly. Each of the assemblies 35 and 36 comprises a switching blade 38 adapted to move between the contacts 39 and 40. Switch blade 38 is electrically insulated from the contacts 39 and 40 by the spacers 41. Contact 39 and switch blade 38 are connected in the circuit containing the field coils 10 and 11. When the blade 38 contacts the element 39, the circuit to the field coils is closed and the coils may be energized by any suitable power source. The upper contact 40 is connected with switch blade 38 in the circuit of the device to be actuated by the relay.

As best shown in Figures 6 and 8, movement of switch blade 38 from one contact to the other contact is effected through a cam 44 that is keyed or otherwise fastened on the rotor shaft 24 so as to rotate with the shaft. The cam follower 45, associated with the cam 44, pivots on the stud 46 journaled in clamping plate 27. A metal yoke 47 is fastened to each of the switch blades 38 of the assemblies 35 and 36, being insulated from the blades 38 by spacers 47a, and the yoke carries a roller 48 positioned in the yoke between the switch blades so that the roller will be biased by the spring action of the blades 38 against the contoured edge of cam follower 45. This contoured edge has a recessed portion 49 and an extended portion 50. When the cam follower is swung by the cam 44 to the right as viewed in Fig. 8, the yoke 47 will be moved downwardly by the extended portion 50 of the follower to close the blades 38 against the contacts 39, thereby closing the circuit to the field coils of the relay. When the cam follower is swung to the left, the roller 48 will ride upwardly into the recessed portion 49 of the cam follower, thereby breaking the contact of blades 38 and contacts 39, and then closing the switch blades 38 against contacts 40 to close an auxiliary circuit.

Figures 7 and 8 show the relative positions of the rotor stop 31 and the cam 44 when the relay is in a reset or ready position. In this position, the switch to the field coils is closed, i. e. blade 38 is closed against contact 39. When the coils are energized by a suitable electric impulse, the rotor 22 and the cam 44 will rotate in a clockwise direction moving the cam follower toward the left to a position where the recessed portion 49 of the cam follower becomes aligned with the roller 48. At this point in the rotation of the rotor, the circuit to the field coils will be opened, but the rotor will continue to rotate due to the magnetic pull by its poles to the pole pieces 13 as explained herein above. When the rotor has reached its rest position the switch blades 38 will have closed against the contacts 40 of the auxiliary circuit.

The disc 51 on the front end of the rotor shaft 24 is a means for providing a visual signal that the rotor has operated. This disc has a colored signal portion 52 on one side thereof. When the relay receives an electric impulse, the shaft 24 will rotate the disc 51 and, in the preferred embodiment of the invention wherein the rotor rotates approximately 180° upon actuation of the relay, the signal portion will be rotated to the dotted line position shown in Fig. 4. Thus, an attendant will know that a signal has been received by the relay and that the relay has operated, whereupon he will reset the relay by turning the disc back to its first position thereby moving the stop 31 on the rotor to the bias spring 32, so that the relay can again operate when another electric signal is developed.

Without further description it is thought that the features and advantages of the invention will be readily apparent to those skilled in the art, and it will, of course, be understood that the principle thereof may be embodied in other arrangements without departing from the spirit of the invention and scope of the appended claims.

We claim:

1. In an electric relay, a direct current motor including a permanently magnetized rotor having diametrically opposite poles and electromagnet means presenting a pole adjacent to said rotor whereby either of said poles of the rotor will be attracted toward said electromagnet pole when said electromagnet is deenergized, and stop means preventing complete rotation of said rotor but permitting rotation of at least 180° and including

a stop arm on a fixed support and a stop finger connected to said rotor to abut the stop arm and prevent said rotor from being rotated into a position to bring its poles into exact alignment with said electromagnet pole, whereby said rotor will rotate from a reset or ready position in which said stop finger rests against said stop arm to its inactive position when said electromagnet is energized, said stop arm being resilient and biasing the stop finger to rotation of the permanent magnet in one direction.

2. In a direct current electric relay as defined in claim 1, the addition of a cam mounted on said rotor, a cam follower pivoted adjacent one end on a fixed support and swingable by said cam between two positions, the swinging end of said follower having a follower surface including a projection and a recessed portion, a first switch in circuit with said electromagnet means and comprising a spring blade as one arm thereof and a contact element as the other arm of said switch, said spring blade being biased toward said contact element and having connected thereto a part that engages said follower surface whereby said switch is closed when said part is aligned with the recessed portion of said follower surface and opened when aligned with said projection, a second switch attached for connection into the circuit of a mechanism to be controlled and including a second contact element as one arm thereof and said spring blade as the other arm of said second switch, said contact elements being on opposite sides of said blade whereby said first switch is opened when said second switch is closed and vice versa.

3. In an electric relay adapted to be driven by direct current, the combination of a mounting plate having spaced openings therein, two spaced apart and substantially parallel electromagnet cores each rigidly mounted in one of said openings with pole pieces extending from one side of said plate and shank portions extending from

the other side of said plate, coils of insulated wires on said shank portions for magnetizing said cores, the polarity of said pole pieces being opposite to each other when current is passed through said coils, a clamping plate extending between and rigidly fixed upon the ends of said pole pieces, said mounting plate and clamping plate being substantially parallel to each other, a bearing journaled in said bearings with its axis parallel to the axes of said pole pieces, a permanent magnet mounted on and to rotate with said shaft and between said pole pieces, a cam coaxially mounted on said shaft, a follower for said cam pivoted on said clamping plate and having a cam follower surface, a switch in circuit with said coils, said switch including a spring blade biased toward and having connected thereto a part that engages said cam follower surface of said cam follower, whereby said switch is open when said cam actuates said follower to one position on said pivot in one direction and said switch is closed when said cam rotates said follower to another position in an opposite direction.
